MINIATURE PHONOGRAPH

John H. Wilhelm, Hamilton Beach, Long Island,
N. Y., assignor to Voices, Incorporated, Newark,
N. J., a corporation of Delaware

Application March 27, 1934, Serial No. 717,590

26 Claims. (Cl. 274—1)

This invention relates to phonographs, and more particularly to a short record miniature phonograph.

The object of the present invention, generally, is to provide a simple form of miniature phonograph suitable for use as an advertising novelty or toy, or for use in dolls.

Dolls have heretofore been provided with inexpensive voices, such as a crier, and the bellows of such voices have also been valved to articulate a simple word like "Mama"; but reproduction of true speech has not been obtainable. In one aspect, an object of my invention is to produce an inexpensive short-playing voice which will enunciate true speech. In the course of considerable experimentation and development of phonographs for dolls, I have been impressed with the complexity of the mechanisms required for lifting and resetting the stylus, particularly because the phonograph must play in any position and must be automatic or self-controlled. Considered in another aspect, an object of my invention is to eliminate all such mechanisms and to thereby greatly simplify the phonograph. I find that by completely discarding the idea of simulating the construction and operation of a large phonograph on a small scale, I am enabled to fulfill the foregoing objects by using a record having only a single continuous circular sound groove, for such a record may be engaged by a stylus permanently mounted in one position.

More particular objects of my invention center about the sound reproducing mechanism per se, and are: to provide an inexpensive light-weight diaphragm; to eliminate the necessity for a horn or sound amplifier; to enlarge the diaphragm and the record to substantial diameter while using the same in a small compact casing; and generally to reduce the weight and cost of the phonograph to a minimum while obtaining clear loud sound reproduction though of short duration.

Further objects of my invention center about the driving mechanism for the phonograph, and are: to provide flat compact mechanism for rotating the record; to eliminate, if desired, the usual relatively heavy driving spring for rotating the record; to provide flat compact inexpensive yet effective governor mechanism; to insure rotation of the record in only one direction; and, finally, to provide modified driving mechanisms one of which may be suitable for rotating the record only a single revolution at a time, while another may be used for continuous rotation of the record.

To the accomplishment of the foregoing and such other objects as will hereinafter appear, my invention consists in the miniature phonograph elements and their relation one to another, as hereinafter are more particularly described in the specification and sought to be defined in the claims. The specification is accompanied by drawings in which:

Fig. 1 is a section taken through a phonograph embodying features of my invention;

Fig. 2 is a section taken in the plane of the line 2—2 of Fig. 1 and showing the drive mechanism;

Fig. 3 is a section taken in the plane of the line 3—3 of Fig. 1 and shows the governor mechanism;

Fig. 4 is a section taken in the plane of the line 4—4 of Fig. 1 and illustrates the single revolution stop mechanism;

Fig. 5 is a section taken in the plane of the line 5—5 of Fig. 1;

Fig. 6 is a modification driven by a rack;

Fig. 7 is a modification driven by a crank;

Fig. 8 shows the record;

Fig. 9 is a section through a modification; and

Fig. 10 is a section taken in the plane of the line 10—10 of Fig. 9.

Referring to the drawings, the phonograph comprises a preferably cylindrical casing C having an open and a closed end, a vibratile diaphragm D which closes the open end of the casing, a sound record R located behind and substantially parallel to the diaphragm D, said record having only a single sound groove, as is best shown in Fig. 8, a stylus S permanently mounted for constant engagement with the sound groove of record R, a governor G for regulating the speed of the phonograph, and drive mechanism located at the closed end of casing C.

Considering the phonograph of Figs. 1—5 in greater detail, the casing C is preferably made up of three dished or cup-like pieces of sheet metal. The first consists of a face portion 12 and a flange portion 14, the face portion 12 being cut away for most of its area, as is indicated at 16, for free sound discharge. The second consists of a face or end portion 18 and a flange 20.

The flanges 14 and 20 are telescopically related and fit together to form the exterior of the casing. The third member consists of a face portion 22 and a flange 24, the flange 24 being dimensioned to fit closely within the flange 20, and the disc 22 acting as a partition or bearing wall between the ends of the casing. A plurality, say three, tabs of metal 26 are struck from partition

22 and bent outwardly away from flange 24. At

50 55

corresponding points around the periphery of the casing, the flange 14 is cut to form slots 28 which receive screws 30, the latter being threaded into flange 20 and tabs 26. The screws 30 thus

5 hold the parts 18 and 22 in fixed relation, and also hold these parts in adjustable relation to the outermost member 14.

The diaphragm D is preferably made of paper or light parchment, and given a conical shape

10 such as has been highly developed for use in radio loud speakers. The edge portion 32 of the diaphragm is secured to the casing within the face portion 12. The diaphragm is preferably corrugated, as shown at 34, to increase the flexi-

15 bility of the same. The center 36 of the dia- phragm is connected to a light stylus arm 38. The stylus arm is pivotally mounted near the casing wall. In the present case a thin leaf

20 spring 40 is clamped at one end between the parts 38 and 42 of the complete stylus arm, and is clamped at its other end between blocks 44

25 and 46 fixedly mounted on the casing wall. The stylus S is carried directly in the collar 42 of the stylus arm, and extends toward and directly en-

25 gages the record R. The stylus is, of course, located directly in the single sound groove 48 (see Fig. 8) of the record. The contact pressure be-

30 tween the stylus and the record is fixed when the phonograph is initially assembled, this being

35 made possible by reason of the screw and slot construction 30, 28 heretofore referred to. The blocks 44, 46 supporting the stylus arm are prefer-

35 ably themselves mounted on a block 50 of rubber which is independently secured to the casing

40 wall. Such an intermediate cushion relieves the stylus of excessive pressure, should the initial adjustment be faulty or the record be out of true. I have, however, obtained satisfactory results even with a rigid mounting directly upon the

45 casing wall devoid of any form of intermediate cushion.

The record R is here illustrated as a disc record having a lateral sound groove. The record is substantial in diameter, it having a diameter 45 nearly equal to that of the casing, which, of course, is desirable in order to obtain substantial sound reproduction while using only a single sound groove. The record is backed up by a record support plate or table 52, and the record and

50 table are clamped to a record shaft 54 by means of a washer 56 and nut 58 which clamp the record and record support against a collar 60 formed on the record shaft 54. Record shaft 54 is rotatably supported in bearings formed at the center of the plates 18 and 22 of the casing.

The governor G comprises relatively large flat weight arms 62 and 64, best shown in Fig. 3, which are respectively pivotally mounted at 66 and 68 on the record support 52. Weight arm

60 64 carries a brake shoe 72 adapted to ride directly on the inner cylindrical wall of flange 24 of the casing. The weight arms 62 and 64 are interconnected by a link 74 freely pivoted on the collar 60 of the record shaft. Link 74 insures

65 simultaneous opposite movement of the weight arms, so that the effect of both weight arms is applied to the brake shoe 72. It is preferred to use two or more weight arms in symmetrical ar-

70 range ment in order to balance the governor mechanism. I find it better to use a single brake shoe on one of two interconnected arms, than to use separate brake shoes on two independently movable arms.

Much of the simplification of this governor 75 arises from its being mounted directly on the

record support, and this in turn is made possible because of the large dimension of the governor weights and the large radius at which they function.

The mechanism so far described is common to the phonographs of Figs. 6 and 7 as well as Fig. 1, for these species differ only in the drive mechanism of the phonograph. Referring first to Figs. 1 through 5, I illustrate drive mechanism actuated by a pull cord 80. This pull cord is connected at 82 to a drum 84 about which it is wound. Drum 84 is mounted and freely rotatable on record shaft 54. A spiral take-up spring 86 is connected to the casing at 88 and to the drum at 90. The drum carries a stop arm 92, while the casing 15 is provided with a stop 94 cooperating therewith, this stop being struck outwardly from partition plate 22. It will be evident that by pulling cord 80, the drum 84 may be rotated for a single revolution in one direction, and that upon release of 20 cord 80, the drum is rotated in opposite direction by spring 86. In the present case it is preferred to drive the phonograph while pulling the cord, so that the spring 86 may be light and inexpensive. It is possible, however, to reverse this 25 arrangement and to use a heavy spring which itself drives the phonograph, the cord 80 then serving merely to rewind the spring.

Rotation of the drum 84 is imparted to record shaft 54 through clutch means operating to drive 30 the record in only one direction. For this purpose the record shaft 54 is provided with an arm 96 forcibly driven on the record shaft, and drum 84 is provided with a triangular projection or driving pawl 98. Upon rotation of the drum in 35 one direction, the arm 96 is driven therewith by projection 98, but upon reverse rotation of the drum the arm 96 remains stationary. To prevent the possibility of reverse movement of arm 96, particularly at the end of the return move- 40 ment of the drum when the sloping side of projection 98 reaches and bears against the arm 96, the phonograph is preferably provided with stop mechanism here exemplified by the triangularly-shaped stop 100 struck outwardly from partition 45 22 and best shown in Fig. 5. Arm 96 is readily moved past stop 100 in the forward direction but not in the reverse direction.

For successful operation of the mechanism thus far described, it is highly desirable that 50 drum 84 go through a complete revolution which must not be diminished by even the amount of the width of a stop arm such as the stop arm 92. In fact, for safety the drum 84 may be allowed to rotate a slight amount more than a revolution. 55 For this purpose the stop 94 heretofore referred to is stepped to form a part 94' spaced from the part 94 by an amount equal to or greater than the width of the stop 92, this being best shown in Fig. 4. The part 95 interconnecting the stops 94 60 and 94' is located in alignment with the stop arm 92 and provides a sloping or rounded approach for the stop arm. Consequently, when stop arm 92 moves in one direction, it is brushed slightly sidewardly until it reaches the stop 94, whereas 65 when it moves in opposite direction it is brushed slightly sidewardly on the other side of the connecting portion 95 until it reaches the stop 94'. In this way the drum may be given one complete or even slightly more than one complete revolu- 70

A modified form of drive mechanism is shown in Fig. 6. In this case the phonograph is actuated by a push rod 102 extending out of the casing and carrying a push knob 104. The rod 75

102 is a rack meshing with a pinion 106 which is freely rotatable on record shaft 54 and which replaces the drum 84 heretofore described. The pinion 106 carries a disc 108 having a triangular 5 driving pawl 110 cooperating with the arm 96 of the record shaft. The rack 102 is guided by an extension 112 passing through the opposite side of the casing. A compression spring 114 around rod 112 acts to restore the rack to initial position. The rotation of pinion 106 depends upon 10 the gear ratio between the rack and pinion, and may be adjusted to permit only a single revolution. However, if desired the pinion may be made smaller and the parts arranged for a multiple 15 of one revolution, say two revolutions, in which case the record is played twice for each operation of the push rod.

In Fig. 7 I show an even simpler form in which the record shaft 54 has a crank 120 mounted directly thereon. The record may be played repeatedly by simply turning the crank. To prevent reverse rotation of the record, the shaft 54 is provided with a slip spring 122 having one end anchored on the casing at 124 and being wound 25 about the shaft in such direction that it is loosened when the record is turned in proper direction, but is tightened and locked if attempt is made to turn the record in reverse direction. It will be appreciated that if desired the crank 30 120 may be free from the record shaft and coupled thereto by an appropriate clutch transmitting rotation in only a single direction. In such case the crank may be turned backwardly but without causing rotation of the record.

35 In Figs. 9 and 10, I illustrate a modified form of phonograph which differs most importantly in the mounting or suspension of the stylus. It is desirable to make possible the manufacture of these articles at very low cost and manufacturing 40 tolerances must therefore be large. Furthermore, the record may not run true on the shaft. It is therefore desirable that the stylus S be so supported as to be yieldable both radially and axially of the record without however interfering 45 with successful sound reproduction.

In the arrangement of Figs. 9 and 10, these results are obtained by attaching the stylus supporting spring 140 (corresponding to spring 40 in Fig. 1) to a support ring 142 which extends around 50 the speaker diaphragm D. Ring 142 is provided with a plurality of hooks 144 in which are caught loops 146 of a continuous rubber band 148. Band 148 extends around the exterior of the casing C and the loops 146 are drawn into the casing 55 through holes 150. To prevent creeping of the band and consequent change in adjustment or location of the stylus, the band may be locked in place by a strip of paper 152 cemented around the band and the exterior of the casing.

60 The casing is, in this instance, provided with a separate end cap 154 on which the elastic band is mounted. To facilitate assembly of the casing, the cylindrical part 156 thereof is slotted at 158 in registration with the perforations 150 and the 65 loops 146.

In order to increase the compactness of the entire phonograph unit, diaphragm D is reversely dished at the central portion 160, thereby making possible the interposition of an elastic strut or pin 70 162 between diaphragm D and the stylus arm 138. This construction accommodates the rather free floating of the stylus mounting in operation.

The drive mechanism of the phonograph here illustrated corresponds to that shown in Figs. 1 75 through 5 of the drawing, but the speed control

mechanism has been simplified by elimination of the governor. Instead, a disk of felt or equivalent material 164 is placed between the record R (or the record support if the record is separate from the record support) and the intermediate or partition plate 166 in the casing. The record shaft is so dimensioned and mounted as to create frictional resistance to rotation by the felt, and inasmuch as the record only rotates a single revolution, I find it possible to obtain adequate speed regulation by this simple means. The felt disk construction is, of course, much more inexpensive than a true governor mechanism.

It is believed that the mode of constructing and using, as well as the many advantages of my improved miniature phonograph, will be apparent from the foregoing detailed description thereof. The mechanism is simple, inexpensive, light in weight, and compact. The sound reproduction obtained is loud and clear although of short duration. The mechanism is devoid of means to lift and reset the stylus, and instead the stylus is permanently fixed in engagement with the sound groove of the record. The record may be played in any position. The sound box mechanism is simplified and lightened by the use of a large diaphragm mounted across the open end of the casing. No horn or equivalent amplifying chamber is employed. The device may be used as an advertising novelty to repeat the name of a product 20 or an advertising slogan. It may also be used as a voice for a doll.

It will be apparent that while I have shown and described my invention in preferred forms, many changes and modifications may be made in the 25 structures disclosed, without departing from the spirit of the invention, defined in the following claims.

I claim:

1. A miniature phonograph comprising a record 40 having only a single continuous circular sound groove, a record shaft for supporting and rotating the record, means to rotate said shaft in one direction, means to prevent rotation of the shaft in opposite direction, a diaphragm, and a stylus connected thereto and engaging said record sound groove.

2. A miniature phonograph comprising a record 50 having only a single continuous circular sound groove, a record shaft for supporting and rotating the record, means movable in opposite directions but arranged for rotating said shaft in only one direction, means to positively prevent rotation of the shaft in opposite direction, a speed limiting means, a diaphragm, and a stylus connected thereto and permanently fixed in engagement with said record sound groove.

3. A phonograph comprising a compact, flat-ended cylindrical casing, a cone speaker diaphragm occupying and closing one end of said casing, a record and record rotating mechanism mounted in said casing, behind said diaphragm, a stylus engaging the record, and a stylus arm interconnecting the diaphragm and stylus.

4. A miniature toy phonograph comprising a 65 compact cylindrical casing open at one end, a cone speaker diaphragm closing said end of the casing, a disc record of substantial diameter arranged parallel to and behind said diaphragm within said casing, record rotating mechanism mounted in said casing, and a stylus arm connected to said diaphragm and pivoted in said casing and carrying a stylus extending toward and engaging the record.

5. A miniature phonograph comprising a cas- 75

- ing, a cone speaker diaphragm at one end of said casing, a disc record of substantial diameter arranged concentric and parallel to and behind said diaphragm within said casing, record rotating mechanism mounted in said casing between the record and the opposite end of said casing, and a stylus arm connected at one end to the center of said diaphragm and pivoted at its opposite end near one side of the casing and carrying at the latter end a stylus extending toward and engaging the record for lateral vibration.
6. A phonograph having a compact flat-ended cylindrical casing, a cone speaker diaphragm mounted at and occupying one end of said casing, a record and record moving mechanism mounted in said casing, behind said diaphragm, a stylus, a stylus arm interconnecting said diaphragm and stylus, said record having a single continuous sound groove receiving the aforesaid stylus.
7. A miniature toy phonograph having a cylindrical casing, a speaker diaphragm mounted at and occupying one end of said casing, a record of substantial diameter arranged coaxial with and behind said diaphragm within said casing, record rotating mechanism mounted in said casing, a stylus, a stylus arm interconnecting said diaphragm and stylus, said record having a single continuous circular sound groove receiving the aforesaid stylus.
8. A phonograph having a casing, a speaker diaphragm at one end of said casing, a disc record of substantial diameter arranged parallel to and behind said diaphragm within said casing, record rotating mechanism mounted in said casing between the record and the opposite end of the casing, a stylus arm connected at one end to said diaphragm and pivoted on a ring floatingly mounted within the casing.
9. A miniature phonograph having a cylindrical casing large in diameter relative to its length, a speaker diaphragm closing one end of said casing, a disc record of substantial diameter arranged parallel to and behind said diaphragm within said casing, record rotating mechanism mounted in said casing between the record and the opposite end of the casing, a stylus arm connected at one end to the center of said diaphragm and pivotally mounted at its opposite end on a stationary leaf spring and carrying at the latter end a stylus extending toward the record, said record having a single continuous circular sound groove located concentrically on said record and receiving the aforesaid stylus, said stylus being permanently fixed in engagement with said sound groove.
10. A miniature phonograph comprising a cylindrical casing, a diaphragm mounted at and occupying one end of said casing, a record, governor means rotatable therewith and including a pair of oppositely disposed weight arms interconnected by a link for simultaneous movement, one of said weight arms carrying a brake shoe adapted to run on and contact with the inside of said cylindrical casing, and means to drive said record.
11. A phonograph having a casing, a speaker diaphragm at one end of said casing, a record and record support of substantial diameter arranged parallel to and behind said diaphragm within said casing, a stylus, a stylus arm connected to said diaphragm and stylus, said record having a single continuous circular sound groove located concentrically on said record and receiving the aforesaid stylus, governor means including a pair of oppositely disposed weight arms piv-
- totally mounted on said record support and interconnected by a link for simultaneous movement, one of said weight arms carrying a brake shoe, and means to drive said record.
12. A toy phonograph having a compact cylindrical casing, a speaker diaphragm mounted at and occupying one end of said casing, a record behind said diaphragm within said casing, a stylus arm connected to said diaphragm and carrying a stylus extending toward the record, said record having a single continuous circular sound groove receiving the aforesaid stylus, and means to drive said record, said means including a flat drum, a pull cord wound on said drum and extending out of the casing, a spring connected to said drum, and means causing said drum to rotate the record in one direction only.
13. A miniature phonograph having a casing, a speaker diaphragm closing one end of said casing, a record of substantial diameter arranged parallel to and behind said diaphragm within said casing, a stylus arm connected to said diaphragm and carrying a stylus extending toward the record, said record having a single sound groove receiving the aforesaid stylus, and means to drive said record, said means including a flat drum behind said record, a pull cord wound on said drum and extending out of the casing, a stop for limiting the rotation of the drum to a single revolution, a cord take-up spring connected to said drum, and means causing said drum to rotate the record in one direction only.
14. A miniature phonograph having a cylindrical casing large in diameter relative to its length, a speaker diaphragm closing one end of said casing, a disc record and record support of substantial diameter arranged parallel to and behind said diaphragm within said casing, a stylus arm connected at one end to the center of said diaphragm and pivoted on a ring floatingly held by elastic means extending from the ring to the casing wall, said record having a single circular sound groove permanently receiving said stylus, and means to rotate the record.
15. A miniature toy phonograph having a compact casing, a speaker diaphragm at one end of said casing, a record behind said diaphragm within said casing, a stylus arm connected to said diaphragm and carrying a stylus extending toward the record, said record having a single continuous circular sound groove receiving the aforesaid stylus, and means to drive said record, said means including a reciprocable rack having an actuating knob extending out of the casing, and a pinion meshing with said rack.
16. A miniature phonograph having a compact cylindrical casing, a speaker diaphragm closing one end of said casing, a record of substantial diameter arranged behind said diaphragm within said casing, a stylus arm connected to said diaphragm and carrying a stylus extending toward the record, said record having a single continuous circular sound groove receiving the aforesaid stylus, and means to drive said record, said means including a reciprocable rack having an actuating knob extending out of the casing, a pinion meshing with said rack, and means interconnecting the pinion and record for rotation of the record in only one direction.
17. A miniature toy phonograph having a compact cylindrical casing, a cone speaker diaphragm at one end of said casing, a record behind and parallel to said diaphragm within said casing, a stylus arm connected to said diaphragm and carrying a stylus extending toward the record, said

- record having a single continuous sound groove receiving the aforesaid stylus, and a crank projecting from the casing for driving the record.
18. A miniature phonograph having a casing, a speaker diaphragm closing one end of said casing, a record and record support arranged parallel to and behind said diaphragm within said casing, a stylus arm connected to said diaphragm and carrying a stylus extending toward the record, a said record having a single continuous circular sound groove receiving the aforesaid stylus, speed limiting means rotatable with said record support, and means to drive said record, said means including a crank, means coupling the same to said record, and means preventing rotation of said record in reverse direction.
19. A toy phonograph having a compact cylindrical casing, a speaker diaphragm mounted at and occupying one end of said casing, a record behind said diaphragm within the casing, a stylus arm connected to said diaphragm and carrying a stylus extending toward the record, and means to drive said record, said means including a flat drum mounted behind said record, a pull cord wound on said drum and extending out of the casing, and a spring connected to said drum, said casing, diaphragm, record, and drum all being arranged coaxially.
20. A toy phonograph having a compact cylindrical casing, a cone speaker diaphragm mounted at and occupying one end of said casing, a record of substantial diameter behind said diaphragm within the casing, a stylus arm connected to said diaphragm and carrying a stylus extending toward the record, said record having a single continuous circular sound groove receiving the aforesaid stylus, and means to drive said record, said means including a flat drum mounted behind said record, a pull cord wound on said drum and extending out of the casing, a spring connected to said drum, and means causing said drum to rotate the record in one direction only, said casing, diaphragm, record, and drum all being arranged coaxially.
21. A miniature phonograph having a compact cylindrical casing, a speaker diaphragm closing one end of said casing, a record arranged behind said diaphragm within said casing, a stylus arm connected to said diaphragm and carrying a stylus extending toward the record, and means to drive said record, said means including a reciprocable rack having an actuating knob extending out of the casing, a pinion meshing with said rack, and means interconnecting the pinion and record for rotation of the record, said casing, diaphragm, record, and pinion all being arranged coaxially.
22. A miniature phonograph having a compact cylindrical casing, a cone speaker diaphragm closing one end of said casing, a record of substantial diameter arranged behind said diaphragm within said casing, a stylus arm connected to said diaphragm and carrying a stylus extending toward the record, said record having a single continuous circular sound groove receiving the aforesaid
- stylus, and means to drive said record, said means including a reciprocable rack having an actuating knob extending out of the casing, a pinion meshing with said rack, and means interconnecting the pinion and record for rotation of the record in only one direction, said casing, diaphragm, record, and pinion all being arranged coaxially.
23. A miniature toy phonograph having a compact cylindrical casing, a speaker diaphragm at one end of said casing, a record behind and parallel to said diaphragm within said casing, a stylus arm connected to said diaphragm and carrying a stylus extending toward the record, a crank projecting from the casing for driving the record, and means preventing rotation of the record in reverse direction, said casing, diaphragm, record, and crank all being arranged coaxially.
24. A miniature toy phonograph having a compact cylindrical casing, a cone speaker diaphragm at one end of said casing, a record of substantial diameter mounted behind and parallel to said diaphragm within said casing, a stylus arm connected to said diaphragm and carrying a stylus extending toward the record, said record having a single continuous sound groove receiving the aforesaid stylus, a crank projecting from the casing for driving the record, and means preventing rotation of the record in reverse direction, said casing, diaphragm, record, and crank all being arranged coaxially.
25. A miniature toy phonograph having a cylindrical casing, a speaker diaphragm closing one end of said casing, a disc record and record support arranged parallel to and behind said diaphragm within said casing, a stylus arm connected at one end to the center of said diaphragm and pivoted on a large-diameter ring floatingly held by elastic means extending from the ring to the casing wall, and means mounted behind said record for rotating the same, said casing, diaphragm, ring, record, and record rotating means all being arranged coaxially.
26. A miniature toy phonograph having a cylindrical casing large in diameter relative to its length, a cone speaker diaphragm closing one end of said casing, a disc record and record support of substantial diameter arranged parallel to and behind said diaphragm within said casing, a stylus arm connected at one end to the center of said diaphragm and pivoted on a large-diameter ring floatingly held by elastic means extending from the ring to the casing wall, said record having a single circular sound groove permanently receiving said stylus, and means mounted behind said record for rotating the same, said means including a flat drum, a pull cord wound on said drum and extending out of the casing, a spring connected to said drum, and means causing said drum to rotate the record in one direction only, said casing, diaphragm, ring, record, and drum all being arranged coaxially.

JOHN H. WILHELM.
